UNITED STATES PATENT OFFICE

HERMANN KERGEL, OF DRESDEN, GERMANY, ASSIGNOR TO THE FIRM OF SACHSENWERK, LICHT- UND KRAFT-AKTIENGESELLSCHAFT, OF NIEDERSEDLITZ, NEAR DRESDEN, GERMANY

MULTIPOLAR OIL-BREAK SWITCH

Application filed August 7, 1924, Serial No. 730,577, and in Germany October 8, 1923.

This invention relates to a multipolar oil break switch particularly adapted for use on high voltages, and the object of the invention is the provision of a switch of this type having a transverse or crossbar carrying knife blades or other contacts, and which is operated from a single point so that all the contacts are simultaneously actuated, as will be hereinafter more particularly described.

In the drawing Figure 1 is an elevation of a multipolar oil break switch made in accordance with my invention.

Fig. 2 is a plan of the same showing the cap or cover removed.

Fig. 3 is a view similar to Fig. 1 showing another form of the invention.

Fig. 4 is a plan of the structure shown in Fig. 3.

Fig. 5 is a sectional elevation of a third form of the invention.

Fig. 6 is a plan of the same.

Fig. 7 is a sectional elevation of a fourth form of the invention, and

Fig. 8 is a plan of the same.

Referring to the drawings and particularly to Figs. 1 and 2, the device made in accordance with my invention as therein illustrated comprises a plurality of insulating tubes *a* inclined in the form of a pyramid and connected at their upper ends in a hub and at their lower ends by brace bars *b*. At the lower end of each of the insulating tubes *a* the same is fitted with a contact knife *d* or other form of contact. The upper ends of the insulating tubes *a* or the hub in which they are connected are mounted to slide on a guide rod *g*. The upper ends of the insulating tubes *a* are pivotally connected to one end of a link *c*, the opposite or upper end of which is pivotally connected to a lever *f* as indicated at the pivotal or working point *e* which is the sole means of simultaneously actuating the insulating tubes and the knife blades or other contacts carried thereby.

By this structure as will be readily apparent, the apparatus may be designed to work on any voltage and to effect a substantial saving in the use of oil and of economy in space because of the compactness of the device.

In Figs. 3 and 4 the insulating tubes *a* are employed in sets, each comprising tubes disposed at an angle to each other and each set of tubes being connected to the hub *h* in positions spaced at 120°. The tubes *a* carry the knife blade contacts and slide on the guide rod *g* and are also connected by a link *c* to the operating lever *f* in a manner similar to that hereinbefore described. In this structure in order to further obviate the possibility of short circuits, the device may be provided with insulating partition walls indicated at *i*.

In order to ensure a more positive and quicker operation of the switch particularly in breaking the circuit, the guide rods as shown in Figs. 5 to 8 inclusive may be provided with a spring member *k* cooperating between a nut *l* and the hub by which the insulating tubes and contact members slide on the guides *g*. The tension of the spring *k* may be regulated by adjusting the position of the nut *l* with which it cooperates, thereby also controlling and determining the speed with which the switch may be caused to open. Also referring particularly to Figs. 7 and 8, it will be seen that instead of employing a single guide tube a pair of the same may be employed, and of course, obviously, the number of guide members employed forms no part of the present invention. It will also be understood that inasmuch as the actuating spring member *k* are placed inside these guide members, the guide members act as protectors for the springs when the spring mechanism is used.

I claim as my invention:

1. In a multi-polar oil break switch for use in high tension plants, a vessel, a cen-

trally disposed guide member, a hub slideable on the said guide member, a frame of pyramidal form comprising an angular base and arms connected at corresponding ends to the corners of the base, extending upwardly and connected at their opposite ends to the said hub, bridging members connected to and carried at the corners of the said base and the lower end of the said arms, a plurality of fixed terminal contacts, and a unitary means for actuating the said hub and frame for moving the said bridging members relatively to the said fixed terminal contacts.

2. In a multi-polar oil break switch for use in high tension plants, a vessel, a centrally disposed guide member, a hub slideable on the guide member, a pyramidal frame comprising a triangular base and tubes of insulating material extending from the corners of the said base upwardly to and connected with the said hub, a set of bridging members each connected at a corner of the said triangular base, a plurality of fixed terminal contacts, and a unitary means for actuating the said hub and pyramidal frame for moving the said bridging members relatively to the said fixed terminal contacts.

3. In a multi-polar oil break switch for use in high tension plants, a vessel, a hollow centrally disposed guide member, a hub mounted to slide on the said guide member, a pyramidal frame comprising an angular base and a plurality of arms connected at corresponding ends to the corners of the said angular base and extending upwardly therefrom with the opposite ends secured in the said hub, a plurality of bridging members connected to and carried by the base of the said pyramidal frame at the corners thereof, a corresponding number of fixed terminal contacts, means within the centrally disposed guide cooperating with the said hub and its pyramidal frame for accelerating the movement thereof in one direction, and a unitary means for actuating the said hub and pyramidal frame for moving the said bridging members relatively to the said fixed terminal contacts.

4. In a multi-polar oil break switch for use in high tension plants, a vessel, a hollow centrally disposed guide member, a hub mounted to slide on the said guide member, a pyramidal frame comprising a triangular base and a plurality of arms connected at corresponding ends to the corners of the said triangular base and extending upwardly therefrom with the opposite ends secured in the said hub, a plurality of bridging members connected to and carried by the base of the said pyramidal frame at the corners thereof, a corresponding number of fixed terminal contacts, a spring contained within the said hollow centrally disposed guide

and cooperating with the said hub and pyramidal frame for accelerating the movement thereof and the said bridging members in one direction, means for adjusting the tension on the said spring, and a unitary means for actuating the said hub and pyramidal frame for moving the said bridging members relatively to the said fixed terminal contacts.

In testimony that I claim the foregoing as my invention, I have signed my name this 9th day of July, 1924.

HERMANN KERGEL.
